UNITED STATES PATENT OFFICE.

CHRISTIAN G. LEHMANN, OF DETROIT, MICHIGAN.

INCUBATOR.

1,046,204.

Specification of Letters Patent.

Patented Dec. 3, 1912.

Application filed May 9, 1912. Serial No. 696,071.

To all whom it may concern:

Be it known that I, CHRISTIAN G. LEHMANN, a subject of the Emperor of Germany, residing at Detroit, in the county of Wayne and State of Michigan, have invented certain new and useful Improvements in Incubators, of which the following is a specification, reference being had thereto to the accompanying drawings.

10 This invention relates to improvements in incubators and more particularly to means for regulating the heat for such devices.

The object of the invention is to provide simple and efficient means operated by the 15 temperature within the incubator for accurately controlling the heating apparatus whereby an even temperature is maintained within the incubator and further to provide certain other new and useful features in the 20 construction and arrangement of parts all as hereinafter more fully described and particularly pointed out in the claims reference being had to the accompanying drawings, in which—

25 Figure 1 is a longitudinal vertical section through an incubator embodying the invention; and Fig. 2 a plan view of the same.

As shown in the drawings 1 is a casing of the usual construction provided with a 30 double wall and supported upon suitable legs.

2 is a heater of any suitable form and construction having an upwardly extending flue or chimney 3 into the upper end of which 35 extends a flue 4 leading horizontally into the casing 1 near the top thereof. This flue 4 extends across the casing longitudinally thereof near one side, thence across the casing near one end and back the length of 40 the casing to an outlet opening 5 in the top of the casing which opening is controlled by a slide 6. This slide may be moved by the operator to close or open the outlet as desired.

45 The flue 4 is provided with an outlet 7 outside of the casing 1 and near the vertical portion of the flue which extends downward into the chimney 3 of the heater. Adjacent to one side of this outlet 7 is pivoted a 50 damper 9 which is adapted to swing downward across the flue 4 and close the same against the passage of heat into the incubator casing. If desired this damper may be turned to close the outlet 7, when the heat 55 passing through the passage 4 will all be forced to pass through the flue into the cas-

ing. As shown in Fig. 1 the damper may be set in an inverted position when part of the heat will pass out through the outlet 7 and part will pass the damper and enter the cas- 60 ing. The amount of heat entering the incubator may thus be accurately regulated by turning the damper and to so turn the damper and to automatically regulate the heat a thermostat 10 is supported within the 65 chamber of the incubator to engage and operate a lever 11 which is pivoted at 12 intermediate its ends and extends outward through an opening 13 in the end wall of the casing 1. Secured to the pivot or shaft 70 14 of the damper 9 is a lever 15 having a weight 16 at one end and a pointer 17 at its opposite end. A second lever 18 extends substantially at right angles to the lever 15 with one end engaged therewith and its opposite end connected to the outer end of the lever 11 by means of a connecting rod 19. The lever 18 is pivoted intermediate its ends 75 at 20 to a suitable supporting bracket on the end of the casing. An indicator plate 80 21 is adjustably secured to the side of the flue 4 by means of a screw 22 engaging a curved slot 23 in the plate. This plate is provided with graduations and indicating marks over which the pointer 17 moves. 85 The connecting rod 19 passes through an eye or opening in the end of the lever 11 and is screwthreaded at its lower end to receive an adjustable thumb nut 24 so that the length of the rod may be accurately adjusted as de- 90 sired.

As the heat within the incubator chamber increases, the thermostat 10 will be expanded thereby and the lever 11 rocked upon its pivot causing the outer end of the lever to 95 move downward bringing its end into engagement with a nut 24 and pulling upon the rod 19. This pull upon said rod will rock the lever 18 upon its pivot 20 and bring its end into engagement with the lever 15 100 which lever will in turn be lifted, turning the damper 9 downward across the flue and cutting off the passage of the heat from the heater into the incubator chamber. This operation will at the same time be indicated 105 by the pointer 17 moving over the graduations on the plate 21.

When the temperature in the chamber of the incubator falls, the thermostat will contract permitting the inner end of the lever 11 to fall by gravity and its outer end to rise away from the nut 24 on the rod 19. 110

The weight 16 will then operate to turn the lever 15 and swing the damper 9 upward until the downward movement of said lever 15 is arrested by the lever 18 which in turn 5 is held by the nut on the rod 24 coming in contact with the outer end of the lever 11. The damper 9 is thus swung upwardly as the temperature in the casing falls and more heat will be admitted to the casing through 10 the flue.

The device may be set by means of the thumb nut 24 so that it will operate to turn the damper and maintain the temperature in the casing at any desired degree. When the 15 temperature within the casing is normal or at the point at which the device is set to operate and maintain such temperature, the pointer 17 will be in mid position of the plate or at zero, said plate being adjusted by 20 means of its screw 22 when the nut 24 is adjusted to change the normal degree of temperature within the casing so that when said temperature is at the desired or normal point the pointer will be at zero. Any variation 25 from the degree of temperature at which the device is set to operate will thereafter be indicated by the pointer 17 being deflected one way or the other from the zero mark.

30 Obviously, changes may be made in the construction and arrangement of parts without departing from the spirit of my invention and I do not wish to limit myself to the particular form or construction shown.

35 Having thus fully described my invention what I claim is:—

1. In an incubator, the combination with 40 a casing, an air flue extending horizontally into and across the casing and provided with an outlet through the top of the casing, a

heater connected to the outer end of the air flue outside of the casing, said air flue being provided with an outlet opening adjacent to said end to which the heater is connected, a damper pivoted within the air flue to swing 45 across the same and across the outlet opening, a lever connected to the damper to turn the same and provided with a pointer, a thermostat within the casing, adjustable lever mechanism connecting the thermostat 50 and the lever for operating the damper, and an indicator plate adjustably supported adjacent to the pointer.

2. In an incubator, the combination with a casing, of an air flue extending into the 55 casing and provided with an outlet opening adjacent to its outer end, an air heater connected to the outer end of the air flue, a damper pivotally supported within the air flue to be turned across the same and across 60 the outlet opening in said flue, a weighted lever attached to said damper, a lever pivotally supported upon the casing intermediate its ends with one end engaging the weighted lever, a thermostat within the casing, a lever 65 pivoted intermediate its ends with one end engaged by the thermostat, a rod connected to the free end of the lever pivotally supported upon the casing and adjustably connected at its opposite end to the free end of the lever engaged by the thermostat, a pointer carried by the damper, and an indicator plate adjustably supported adjacent to the pointer.

In testimony whereof I affix my signature 70 in presence of two witnesses.

CHRISTIAN G. LEHMANN.
